UNITED STATES PATENT OFFICE.

LAWRENCE ST. CLAIR, OF HAVERHILL, MASSACHUSETTS, ASSIGNOR TO THE REECE
BUTTON HOLE MACHINE COMPANY, OF BOSTON, MASSACHUSETTS, A CORPORATION
OF MAINE.

BUTTONHOLE-FINISHING MACHINE.

1,212,580.

Specification of Letters Patent. Patented Jan. 16, 1917.

Application filed April 21, 1916. Serial No. 92,734.

To all whom it may concern:

Be it known that I, LAWRENCE ST. CLAIR, a citizen of the United States, residing at Haverhill, county of Essex, State of Massachusetts, have invented an Improvement in 5 Buttonhole-Finishing Machines, of which the following description, in connection with the accompanying drawing, is a specification, like characters on the drawing representing like parts.

10 This invention relates to sewing machines of that type wherein the work to be stitched is bent before it is penetrated by the needle so that the latter may enter and emerge from the same side of the work thereby to produce a blind stitch. The invention is herein 15 illustrated as it might be embodied in a sewing machine of this type adapted for finishing the buttonhole pieces for boots and 20 shoes.

25 The main object of the invention is to provide a sewing machine of this type in which the use of a shuttle or bobbin is eliminated and the thread which is concatenated with the needle thread is a continuous one 30 which is taken from a spool or other source of supply in the same way that the needle thread is. The advantage of this is that it obviates the frequent stopping of the machine for placing a new bobbin in the shuttle or for re-winding the bobbin. I accomplish 35 the above object by providing a looper device which co-operates with the needle and is actuated in such timed relation thereto that said looper device will insert a loop of thread through each loop of needle thread while the needle inserts a loop of needle thread through each loop of looper thread. This results in the formation of a double 40 chain stitch.

45 In order to give an understanding of my invention I have illustrated in the drawings a selected embodiment thereof which will now be described, after which the novel features will be pointed out in the appended claims.

50 Figure 1 of the drawings is a top plan view of a sewing machine embodying my invention with the bed plate or work support removed to show better the operative parts of the machine; Fig. 2 is a side view thereof with a side of the frame removed; Fig. 3 is an end view; Fig. 4 is a section on the line 4—4, Fig. 2; Fig. 5 is a sectional view showing the operation of the feed dog;

Fig. 6 is a view of the take-up; Fig. 7 is a sectional view showing the work bent into the work-bending groove and in position to receive the needle; Fig. 8 is an enlarged diagrammatic view showing the character of the stitch formed; Figs. 9, 10, 11 and 12 are diagrammatic views showing the manner in which the looper and needle co-operates to produce the stitch.

1 indicates the frame of the machine on which is supported the top plate 2 which I will hereinafter refer to as the work support since the work *w* to be operated on is placed on the plate 2. This work support is provided with a work-bending groove 3 into 60 which the work *w* is bent to receive the needle as usual in sewing machines of this character. The work is bent into the groove by means of a bender 4 which will be presently described more at length.

5 indicates the needle which is caused to penetrate the work, as shown in Fig. 7, when the latter is bent into the work-bending groove 3, said needle entering and leaving the work on the same side thereof thereby to produce a blind stitch, as usual in machines of this class. This needle is supported by a horizontal needle bar 6 which is situated beneath the work support 2 and is mounted for reciprocation in a horizontal direction 65 in a yoke or frame 7. The needle is given its reciprocation from a driving shaft 15 which is journaled in suitable bearings in the frame and extends at right angles to the direction of the needle. This shaft has an eccentric 16 thereon, the eccentric strap 17 of which has an arm 18 extending therefrom which is pivotally connected at 19 to an arm 20 that in turn is pivoted to the frame at 21. This arm 20 is connected by 70 a link 22 to a pin 23 that is rigid with a collar 24 adjustably secured to the needle bar. The connection 19 between the arms 18 and 20 is an adjustable one, this being provided for by making the arm 20 with the slot 25 in which the pivotal connection 19 can be adjusted. This adjustment provides 75 for varying the length of the stroke of the needle bar, as will be obvious.

80 The needle bar 6 is shifted laterally as it reciprocates as usual in sewing machines for finishing buttonholes thereby to form a zig-zag stitch. For this purpose, the yoke 7 is pivotally mounted at 8 in arms 9 rising from the frame 1, and said yoke has an 85 90 95 100 105 110 115

- 5 arm 10 rigid therewith which is connected by a link 11 with an arm 26 fast on a rock-shaft 12. The rock-shaft 12 has an arm 13 provided with a shoe which operates in the switch cam 14 that is fast on the driving shaft 15. This switch cam mechanism is one commonly used in sewing machines of this type for shogging the needle laterally.
- 10 The looper which co-operates with the needle to form the stitches is shown at 27. As stated above, the looper is constructed to deliver a loop of thread through each loop of needle thread, while at the same time the needle delivers a loop of needle thread through each loop of looper thread. The looper is in the form of a finger having a thread eye 28 near its end and a thread guide 29 through which the looper thread extends. This looper is mounted for vibrating movement in a horizontal direction laterally to the reciprocating movement of the needle and also for vertical swinging movement. The looper is provided with a stem 30 which is adjustably secured in an arm 31 that is pivoted at 32 to a frame 33. The arm 31 has a pin 34 depending therefrom to which is pivotally connected one end of a link 35, the other end of said link being connected to one arm 36 of an elbow lever. This lever is pivoted on a stud 37 rising from the frame and the other arm 38 thereof has a pivotal or ball-and-socket connection with the extension 39 of an eccentric strap 40 that encircles an eccentric 41 formed on the shaft 15. These connections operate to oscillate the looper about its pivot 32 as the shaft 15 rotates.
- 15 The frame 33 on which the looper is mounted is provided with trunnions 410 that are journaled in bearings 42, 43 formed on the frame and one of these trunnions is of considerable length and has fast thereto a forked arm 44 that embraces an eccentric or cam 45 fast on the shaft 15. This eccentric or cam 45 operates through the arm 44 to rock the looper about its trunnions, as will be obvious. The needle thread *n* is led to the needle in usual manner through some suitable tension device (not shown).
- 20 The other thread *l* which is manipulated by the looper, and which I will for convenience hereinafter refer to as the looper thread, is led from a spool or other suitable source of supply through a tension device 46 and thence through a take-up designated generally as 97, and which will be presently described, thence through the thread guide 29 on the looper and through the looper eye 28.
- 25 The manner in which the needle and looper co-operate to concatenate the stitches is illustrated diagrammatically in Figs. 9, 10, 11 and 12. Fig. 9 represents the needle as thrust through the work *w*, it being understood that the work will be bent into

the work-bending groove 3 by the bender, as shown in Fig. 7. As the needle begins its withdrawing movement a loop 47 of the needle thread *n* will be thrown out as usual. The looper is at this time moving in the direction of the arrow Fig. 9, and the frame 33 carrying the looper is so positioned by the cam 45 that the point of the looper will pass beneath the needle and through the needle loop 47, as shown. The needle is then completely withdrawn from the work, as shown in Fig. 10, thus leaving the loop 47 of needle thread around the looper. At this time the looper has completely entered the loop 47 and carried a loop 48 of looper thread through said needle loop 47. The looper is then swung upwardly above the path of the needle and the needle is given its next penetrating thrust, as shown in Fig. 11. As the needle moves forward it passes underneath the looper 27 because the latter has been moved upwardly by the rocking movement of the frame 33, and said needle enters the loop 48 of the looper thread, as shown in Fig. 11, and carries a second needle loop 49 of needle thread through the loop 48 of looper thread. While the needle is in its forward position shown in Fig. 11 the looper is retracted, thus completing the loop 48 of looper thread and shedding the first loop 47 of needle thread. As the needle begins its retracting movement and throws out the loop 49 of needle thread, the looper is moved forwardly again thereby to enter the second loop 49 of needle thread, and the above operations are repeated, thus forming the double chain stitch illustrated in Fig. 8.

The operation of the switch cam shifts the needle bar laterally at each thrust thereof, thus producing the zig-zag effect shown in Fig. 8 and causing the concatenated loops to overlie the thrum ends 50 of the buttonhole.

The bender 4 is herein shown as having a goose-neck shape and as extending down through an opening formed in the work-support 2, said bender being pivoted at 51 to a suitable part of the frame. The bender is given its vibrating work-bending movement by means of a cam 52 fast on the shaft 15, said cam having a face groove therein in which the tail 53 of the bender is received. The end of the bender carries a roll 54 which engages the work. The bottom of the work-bending groove is cut away, as shown at 60, directly beneath the bender and the bent portion of the work is supported on two rolls 55 that are suitably journaled in a stand 59, the purpose of these rolls being not only to sustain the work while the needle is making its penetrating thrust, but also to assist in feeding the work.

56 indicates a feed dog by which the work is fed forward. This feed dog is shown as

bifurcated and as having its two arms situated either side of the rolls 55, see Fig. 1.

The feed I have herein illustrated is the usual four-motion feed, the feed dog being 5 raised against the work, then moved forwardly to feed the work, then being depressed, and then moved rearwardly to its initial position. This feed dog 56 is carried by an arm 57 which is provided with the 10 forked portion 58 that embraces an eccentric 61 formed on the shaft 15. This eccentric gives the feed dog its rising and falling movement, as will be obvious. The arm 57 is fast on a shaft 62 that is journaled in the 15 bearing 63 in the upper end of an arm 64 that is fast to a rock-shaft 65. This rock-shaft 65 is journaled in suitable bearings 66 carried by the frame and has an arm 67 fast thereon that is pivotally connected to a crank 20 pin 68 that is adjustably mounted in a crank disk 69 fast on the shaft 15. These latter connections operate to give the feed dog its backward and forward movement.

Any suitable take-up for the looper thread 25 may be used. That herein shown comprises two parallel arms 70 having eyes 71 at their ends through which the looper thread 7 passes. Situated between these arms and fast on the shaft 15 are two separated disks 30 72 having the shape shown in Fig. 6. 73 is an arm which is secured to the stand 74 and operates between the disks 72, the end of the arm resting on the hub of the disks, as shown in Fig. 6. As the take-up disks rotate, 35 the looper thread passes from one arm 70 to the other around the periphery of the disks 72. As the take-up disks rotate, the thread is caught by the portion 76 thereof and is carried in a loop form over the shaft and 40 between the arm 73 and the over-hanging arm 77, this operation resulting in taking up the thread and setting the stitch. The shape of the arm 73 causes the loop of thread to be shed from the point 76 of the take-up disks 45 and the loop of needle thread then occupies the dotted line position, Fig. 6, it being retained in this position by the hooked end 78 of the arm 77. The take-up disks are provided in their periphery with the notch 79 and when this comes in line with the end 78 of the arm 77 the loop of thread is released and slack thread is thus given up for the formation of the next loop.

I have not herein illustrated any take-up 55 mechanism for the needle thread, but it will be understood that any suitable or usual take-up device may be employed.

While I have illustrated herein a selected embodiment of my invention, I do not wish 60 to be limited to the constructional features shown.

I claim:

1. In a machine for finishing buttonholes, the combination with a work support having 65 a work-bending groove, of a bender to bend

the work into the groove, a horizontally-reciprocating needle operating beneath the work support, a looper for manipulating a looper thread, a rocking frame on which said looper is pivotally mounted, means to oscillate the looper in timed relation with the movements of the needle, and means to rock said frame. 70

2. In a sewing machine, the combination with a work support having a work-bending 75 groove, of a bender for bending the work into said groove, a horizontally-reciprocating needle operating beneath the work support, a driving shaft beneath the work support extending at right angles to the needle, 80 an oscillatory frame having a fork rigid therewith, a cam on said driving shaft co-operating with said fork to oscillate the frame, a looper pivoted to the frame, means for oscillating the looper by rotation of the 85 driving shaft, and means to actuate the needle.

3. In a machine for finishing buttonholes, the combination with a work support having a work-bending groove, of a bender for 90 bending the work into said groove, said groove having an opening therein beneath the bender, means to feed the work, and rolls occupying the opening in the groove and on which the work is sustained when 95 acted on by the bender, said rolls having their axes extending at right angles to the feeding movement, and stitch-forming mechanism.

4. In a buttonhole finishing machine, the 100 combination with a frame provided with a work support having a work-bending groove, of a driving shaft beneath the work support, a horizontally-reciprocating needle situated beneath the work support, means to actuate 105 said needle from the driving shaft, a looper pivoted to oscillate in a direction at substantially right angles to the movement of the needle, an arm connected to said looper, an elbow-lever pivoted to the frame, a link connecting one arm of said lever to the arm of the looper, and a connection between the other arm of said lever and said shaft. 110

5. In a buttonhole finishing machine, the 115 combination with a frame provided with a work support having a work-bending groove, of a driving shaft beneath the work support, a horizontally-reciprocating needle situated beneath the work support, means to actuate said needle from the driving shaft, a looper pivoted to oscillate in a direction at substantially right angles to the movement of the needle, an arm connected to said looper, an elbow-lever pivoted to the frame, a link connecting one arm of said lever to the arm of the looper, a connection between the other arm of said lever and said shaft, and a take-up mechanism for the looper thread mounted on said shaft. 125

6. In a buttonhole finishing machine, the 130

combination with a frame provided with a work support having a work-bending groove, of a driving shaft beneath the work support, a horizontally-reciprocating needle situated beneath the work support, means to actuate said needle from the driving shaft, a looper pivoted to oscillate in a direction at substantially right angles to the movement of the needle, an arm connected to said looper, an

elbow-lever pivoted to the frame, a link connecting one arm of said lever to the arm of the looper, a connection between the other arm of said lever and said shaft, and a rotary take-up mechanism for the looper thread mounted on said shaft. 10

15

In testimony whereof, I have signed my name to this specification.

LAWRENCE ST. CLAIR.
